Primary Examiner — Mark Goodwin*(74) Attorney, Agent, or Firm* — McKee, Voorhees & Sease, PLC(57) **CLAIM**

We claim the ornamental design for a saddle fertilizer tank holder, as shown and described.

DESCRIPTION

FIG. 1 is a perspective view of a saddler fertilizer tank holder.

FIG. 2 is a top plan view of the saddle fertilizer tank holder.

FIG. 3 is a bottom plan view of the saddle fertilizer tank holder; and,

FIG. 4 is a front elevation view of the saddle fertilizer tank holder.

Any portion of the claim not shown in the drawings or described in the specification forms no part of the claimed design.

The subject matter shown in broken lines in the drawings are unclaimed features of the article in which the claimed design is embodied.
